(57) **CLAIM**

The ornamental design for an X-shape suspender, as shown and described.

DESCRIPTION

FIG. 1 is a front perspective view of an X-shape suspender, showing my new design;

FIG. 2 is a top view thereof;

FIG. 3 is a left view thereof;

FIG. 4 is a front side view thereof;

FIG. 5 is a right side view thereof;

FIG. 6 is a rear view thereof;

FIG. 7 is a bottom view thereof; and,

FIG. 8 is a partial enlarged view of area "8" shown in FIG. 1.

The broken lines in the drawings illustrate the portions of the X-shape suspender, which form no part of the claimed design.
